His Attorney.

UNITED STATES PATENT OFFICE

HENRY P. HINDS, OF PITTSFIELD, MASSACHUSETTS, ASSIGNOR TO GENERAL ELECTRIC COMPANY, A CORPORATION OF NEW YORK

ELECTRIC FUSE

Application filed December 18, 1933. Serial No. 415,011.

The present invention relates to protective devices for electrical circuits and more especially to expulsion fuses which comprise a tubular housing or barrel closed at one end and open at the other with terminal contacts at both ends to which a fusible element within the barrel is attached.

Among the objects of my invention are the provision of an improved expulsion fuse which shall operate with certainty when and only when an excess current condition exists on the circuit protected thereby; the provision of an expulsion fuse which shall function effectively on circuits of high potential and small current ratings and embodying such substantial structure that it may be refused by the inexpert without error or injury to the parts.

One embodiment of the invention is shown in the accompanying drawings in which Fig. 1 is an elevation of a complete fuse with a part broken away; Fig. 2 is a vertical section thereof; Figs. 3 and 4 are enlarged fragmentary views of the upper end of the fusible element and its terminal, and Fig. 5 is a vertical section of a primary cut-out box at a reduced scale with my fuse mounted therein.

The special uses for which my fuse is designed are in railway signal systems, farm systems, whereby small currents for farm use are taken from high potential power lines and other systems employing small transformers.

On account of the high voltages and small amperages of the circuits to be protected, the fusible elements are necessarily of very small cross section and in consequence they are fragile and easily dented or otherwise injured in handling, so that the rating may be seriously affected. Moreover, on account of their installation out-of-doors, oxidation by the elements of the fusible element may in the course of a short time so impair the carrying capacity of the fusible element that it disrupts under the ordinary rating of the circuit and it has frequently occurred that fusible elements of unsafely large capacity have been installed.

The main parts or sections of my fusible element consists of tin or tinlead alloy wire

of low melting point, the upper section 1 of which is made single and the intermediate section 2 made double and connected at its lower end to the third or terminal section 3 of copper strip or wire preferably plated with tin or nickel. To provide mechanical strength, the first two sections of the fusible element are mounted upon an asbestos cord 4 which is connected by crimping at its upper end to the terminal disk 6, as shown in Fig. 3, while its lower end is secured to the copper wire section 3 by tightly wrapping the latter thereabout and soldering. In order to take the mechanical strain off of the fuse and keep the long double second section 2 from contacting with the inner wall of the enclosing barrel, it is preferably wrapped several times about a strong, non-conducting, non-carbonizing support such as the asbestos cord 4 and at its upper end is tied about the cord. Owing to the spiral wrapping, the wire is longer than the cord so that the cord takes all mechanical strains which might be imposed on the fuse link. The upper section 1, in which initial fusion takes place, extends from the upper end of the doubled second section and is provided at its upper end with a flexible coil or spiral 5 and soldered to the terminal disk 6. This spiral 5 permits a substantial amount of tilting and bending at the point of juncture with the disk such as is incident to handling by the inexpert without danger of rupture or stretching of the delicate wire 1 of soft metal.

The first two sections 1 and 2 of the fusible element are effectually protected within the housing or barrel from the oxidizing effects of the elements and the lower or third section 3 being of copper well plated and of substantially greater size than the wires of the other sections is well adapted to resist deterioration in normal service.

The terminal disk 6 is preferably made of copper annealed to a dead soft temper with a crown flange 7 on its lower surface adapted to be crimped upon the end of the asbestos cord 4.

The housing or barrel of my fuse consists of a tube 8 of indurated fibre or other stout

insulation material with contact terminals 9 and 10 attached to its opposite ends.

The upper contact terminal 9 has a counter bore at its lower end in which the end of the tube 8 is rigidly secured by indenting the metal of the terminal into the sides of the tube as shown at 11. The terminal 9 extends a considerable distance above the end of the tube and its bore constitutes an extension of the bore of the insulating tube 7. The external lower half of the terminal is rectangular to provide contact surfaces 12 and the upper half is made cylindrical and threaded near its juncture with the rectangular part. An internally threaded thimble 13 having a hand-hold exterior surface is adapted to be screwed down upon the thread of the terminal so that after the fusible element has been installed in the barrel with the terminal disk 6 resting upon the end of the terminal contact 9, the turning home of the thimble serves to clamp the soft copper disk 6 in intimate contact therewith to insure good electrical connection and effectually seal the joint against escape of metallic gases to the threads upon blowing of the fuse.

The lower terminal contact 10 is bored out so as to allow the insulating tube 8 to extend entirely through and project a distance below it, as indicated in Figs. 1, 2 and 5, where the two parts are secured together by indentations 14. The lower end of the terminal contact 10 is provided with a conical surface 15 roughened or knurled and against which the outer end of the third or copper wire section of the fusible element is clamped by a nut 16 engaging threads 17 above the conical surface 15. The upper end of the terminal 10 is made square to provide contact surfaces 18. The object of roughening the conical surface 15 is to insure that the end of the copper wire of section 3 will not be carried around with the nut 16 and the fusible element twisted or otherwise injured.

The cut-out box, as shown in Fig. 5, is a standard article of commerce and need not be described in detail. It has a stationary part 19 in which are secured line terminal contacts 20 and 21 for the reception of the fuse terminals 9 and 10. A door 21 is hinged to the front of the stationary part 19 and the two parts serve to protect the fuse and its connections, while the lower end of the fuse tube 8 projects through the bottom wall 22 so that upon blowing of the fuse the gases and the unconsumed parts of the fusible element will be expelled into the open air.

When the fuse operates on a gradual overload only the single wire section 1 will be volatilized as a rule. In case the overload is relatively heavy, more or less of the double wire section 2 will also be volatilized. Upon blowing of the fuse, any unconsumed metal part thereof and the cord support are ejected from the open end of the tube 8 but left hang-

ing from the lower terminal and thereafter serve as an indicator of the blown condition of the fuse.

What I claim as new and desire to secure by Letters Patent of the United States, is,—

1. A fusible element comprising a short section of single and a long section of double wire of soft metal, a cord of insulating material reinforcing said sections of soft metal wire, and relatively hard metal terminals joined to opposite ends of said cord and said soft metal wire. 75

2. A fusible element comprising an end terminal, a cord of insulating material fastened at one end to said terminal, and a fuse wire supported by said cord and joined to said terminal and provided adjacent the joint with a freely yieldable bent portion. 80

3. A fusible element comprising an end terminal disk with a crown flange projecting from one side, a cord of insulating material having one end connected to said terminal disk by crimping said flange thereon, and a fuse wire supported by said cord and joined to said terminal disk and provided adjacent said joint with a flat spiral alongside said crimped flange. 85

4. A fusible element comprising a disk terminal, a cord of insulating material clamped to one side of said terminal, a thin fuse wire of soft metal supported by said cord and having a flexible coil adjacent the end joined to said disk terminal, and a terminal of relatively thick and hard metal secured to the opposite ends of said cord and said soft metal wire. 95

5. A fuse barrel comprising a tube of insulating material, a terminal contact mounted about one end of said tube and provided externally with a roughened conical surface and a screw thread adjacent said conical surface, and a clamping nut adapted to surround said conical surface and engage said screw thread. 105

6. A fuse barrel comprising a tube of insulating material, a fusible element therein, a contact terminal provided with means for engaging an end of said fusible element and hermetically closing one end of said tube, a second contact terminal secured adjacent the other end of said tube and provided with a knurled conical surface for positive clamping engagement with the other end of said fusible element, and a clamping nut threaded upon said second terminal and adapted to force the fusible element into intimate contact with said knurled conical surface thereof. 115

7. The combination of an insulating barrel provided with metal terminals at its ends, one of which is open, a fusible element disposed within said barrel and comprising an end disk of annealed copper for closing the other end of said barrel, said disk being in electrical connection with the terminal at the 125 130

closed end, a link of fusible metal and a reinforcement cord therefor each having one end attached to said end disk, and a copper strip joined to the opposite ends of said fusible link and said cord within said barrel and extending out the open end thereof and attached to the metal terminal adjacent thereto.

8. The combination of an insulating barrel provided at its ends with clamping metal terminals, one of which is open and the other normally closed, a fusible element disposed within said barrel and comprising an end disk in electrical connection with said closed terminal and provided on its inner side with a crown flange, a cord of asbestos having one end fastened to said end disk by crimping said flange thereupon a link of soft metal fastened to said cord and having one end flexibly joined to said end disk, and a strip of copper protected against oxidation joined to the said cord and said link within the barrel and extending out the open end thereof, bent backwardly and clamped to said open terminal.

9. The combination of an insulating barrel provided at its ends with metallic clamping terminals, one adapted to close the upper end of said barrel and the other surrounding said barrel adjacent the lower open end thereof, a fusible element comprising a member to be clamped to said upper terminal, an insulating cord and a soft metal link each having one end attached to said disk, said link being made double except for a short section at its upper end and fastened to said cord, and a hard metal strip joined to the opposite ends of said cord and said link and extending out the open end of said barrel and clamped to the lower terminal thereof.

In witness whereof, I have hereunto set my hand this 16th day of Dec., 1929.

HENRY P. HINDS.
